United States Patent Office

Des. 193,883
Patented Oct. 16, 1962

193,883

LIQUEFIER

Waldemar Clemente, Rua Dr. Alvaro Alvin 79,
Sao Paulo, Brazil

Filed June 12, 1961, Ser. No. 65,551

Term of patent 14 years

(Cl. D89—1)

FIG. 1

FIG. 2

FIG. 3

FIG. 1 is a front elevational view of a liquefier showing my new design;

FIG. 2 is a left side elevational view thereof; and

FIG. 3 is a top plan view of the liquefier.

The essential features of the design are shown in full lines.

I claim:

The ornamental design for a liquefier, as shown and described.
